INVENTOR
ERICH FERDINAND STEINER

BY
Eduard Spindler
ATTORNEY

UNITED STATES PATENT OFFICE.

ERICH FERDINAND STEINER, OF SONNEBERG, GERMANY, ASSIGNOR TO KARL OHL-
BAUM & SON INC., OF NEW YORK, N. Y., A CORPORATION OF NEW YORK.

VOICE-PRODUCING APPARATUS FOR DOLLS AND OTHER TOY FIGURES.

Application filed April 14, 1927, Serial No. 183,870, and in Germany December 3, 1926.

The present invention relates to a voice producing apparatus for dolls and other toy figures, the air bellows of which is actuated by a pressure weight.

5 An object of the invention is to provide an improved apparatus of the character described including a bellows and pressure weight formed of independent parts which can be separately manufactured economically and readily assembled as required on a commercially profitable basis. The bellows, which forms an independent part of the improved apparatus permits easy insertion and proper setting of the weight and may 10 therefore be manufactured in any desired numbers for stock, each bellows being provided according to requirement with the necessary weight for proper operation, which weight is enclosed either under a bellows cover furnished with a voice producing 15 pipe, or carries such pipe.

The improved construction of the apparatus embodying the invention thus permits simple manufacturing methods of production, and also ensures the production of different voices adapted to the manner in which the voice pipes arranged in the covers or in the covering heads are turned, the same below parts being used.

20 A further object of the invention is to provide a bellows construction having diagonal folds between a lower base plate and an upper ring, said folds being formed to serve as a winding which when the bellows 25 is inflated or deflated produces a turning movement of a part thereof relative a base or stationary part. This construction permits the use of a relatively thick material for making the bellows. The increased 30 thickness of material combined with the diagonal fold construction strengthens the apparatus and assures a vertical bellows movement without requiring the usual center 35 guide rod running through the apparatus.

40 Still another object of the invention is to provide an apparatus of the character described comprising few and simple parts, which shall be cheap to manufacture, easy to assemble to form a rugged structure, and 45 practical and efficient to a high degree in use.

Other objects of this invention will in part be obvious and in part hereinafter pointed out.

The invention accordingly consists in the 55 features of construction, combinations of elements, and arrangement of parts which will be exemplified in the construction hereinafter described, and of which the scope of application will be indicated in the following 60 claims.

In the accompanying drawing, in which is shown one of the various possible illustrative embodiments of this invention,

Figs. 1 and 2 are front elevational and 65 plan views of a voice producing apparatus embodying the invention, showing parts broken away to expose the interior construction;

Fig. 3^a is an elevational view of the bellows with parts broken away.

Fig. 3^b is a partial bottom view of Fig. 3^a.

Fig. 3^c is an elevational view of the pressure weight.

Fig. 3^d is an elevational view of the cover 75 member with parts broken away to show the voice pipe.

Figs. 4 and 5 are front elevation and 80 plan views of a modification, partly broken away.

Fig. 6^a is a front elevational view of the bellows showing a modified construction.

Fig. 6^b is a bottom plan view of Fig. 6^a.

Fig. 6^c is a front elevational view of a modified construction of the pressure weight 85 with parts broken away to show the voice pipe.

Referring in detail to the drawing, a bag-shaped bellows 1 has one end closed by a base plate 2 and has a separate strengthening or rim ring 3 fitted into and securely attached to the other end of the bellows.

This ring 3 forms a receptacle in which a pressure weight 4 is retained. As seen from Figs. 1, 2 and 3^a, 3^b, 3^c, and 3^d, the weight 4 consists of a plate resting as a set-in piece within the rim ring 3 of the bellows 1, and is shaped to provide openings 3' for allowing the air to pass. Preferably said base plate is of polygonal shape so that it does not 90 fill the ring entirely but leaves inside the spaced lateral openings 3' which form the air passages.

The weight 4 is secured in place in the bellows ring 3 by a cover 5. The latter carries a voice producing pipe 6 and constitutes the upper covering piece for the bellows. The bellows parts of the appara-

tus are assembled and fixed by means of the base plate 2 into a tube sleeve 7 closed by a perforated cover 8.

In the modification shown in Figs. 4, 5 and 6^a, 6^b and 6^c, the construction of the bellows is the same as described above, but the pressure weight 4' forms a closure head for the bellows and is preferably made of molded materials, such as porcelain, phenol-condensate products, or the like. This head carries the voice producing pipe 6 which extends through the body of the head.

A feature of the invention is the construction of air bellows 1 between the base plate 2 and the ring 3 in both modifications shown in the drawing, which is provided with diagonal folds acting in the manner of windings, which, when the bellows are inflated or deflated, produce a turning movement of a part of the bellows relative to a stationary part thereof.

This diagonal fold construction permits the use of thicker material for the bellows, whereby a more rugged apparatus is produced and vertical expansion of the bellows provided without the use of a centre guide rod through the apparatus.

The relatively stationary part of the bellows is the same in both modifications shown in the drawing. Said part can be constructed as an independent part and can be interchangeably fitted to form any voice producing apparatus.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention I claim as new and desire to secure by Letters Patent:

50 1. In a voice producing apparatus of the character described, an air bellows, a rim ring of angle cross-section secured to fit into one end of the bellows, and a pressure weight fitted into the ring for inflating and deflating the bellows.

55 2. A voice producing apparatus of the character described comprising an air bellows, a rim ring of angle cross-section secured to fit into one end of the bellows, a pressure weight fitted into the ring for inflating and deflating the bellows, said

weight having an opening to permit the passage of air, and a voice producing pipe movably carried in the path of the flow of air.

60 3. A voice producing apparatus of the character described comprising an air bellows, a rim ring secured to one end of the bellows, a pressure weight fitted into the ring for inflating and deflating the bellows, said weight and ring providing an opening 70 to permit the passage of air, a closure cover cooperating with the ring for retaining the weight therebetween, and a voice producing pipe extending through the cover.

65 4. A voice producing apparatus of the character described comprising an air bellows, a rim ring secured to one end of the bellows, a pressure weight fitted into the ring for inflating and deflating the bellows, said weight being formed of a non-circular piece 80 to provide an air passage, and a voice producing pipe carried by said ring in the path of the flow of the air.

70 5. In a voice producing apparatus of the character described, an air bellows, a rim ring of angle cross-section secured to fit into one end of the bellows, and a pressure weight fitted into the ring for inflating and deflating the bellows, said weight forming a closure 90 for the bellows.

75 6. In a voice producing apparatus of the character described, an air bellows, a rim ring of angle cross-section secured to fit into one end of the bellows, and a pressure weight fitted into the ring for inflating and deflating the bellows, said weight forming a closure 95 for the bellows, and a voice producing pipe mounted to extend through the body of the weight.

80 7. In a voice producing apparatus of the character described, an air bellows formed with folds extending diagonally the length thereof having one end secured to a base plate, a rim ring of angular cross-section secured to fit into the other end of the bellows, and a pressure weight mounted on the ring 105 for inflating and deflating the bellows.

85 8. A voice producing apparatus of the character described comprising an air bellows formed with folds extending diagonally 110 the length thereof having one end secured to a base plate, a rim ring of angle cross section secured to fit into the other end of the bellows, a pressure weight fitted into the ring for inflating and deflating the bellows, said 115 weight and ring formed with a through opening to permit the passage of air, and a voice producing pipe movably mounted in the path of the flow of air.

In testimony whereof I affix my signature.

ERICH FERDINAND STEINER.
